METHOD OF AND APPARATUS FOR WARP
LEASING

Frank H. Kaufmann, Elkins Park, Pa., assignor
to Steel Heddle Manufacturing Company,
Philadelphia, Pa., a corporation of Pennsyl-
vania

Application May 28, 1936, Serial No. 82,163

19 Claims. (Cl. 28—40)

This invention relates to a method of and apparatus for warp leasing, and it has particular relation to a novel manner of separating the warp threads for the insertion of the leasing cords 5 or rods which are used for maintaining an orderly arrangement of the warp threads, usually at one or both ends of the winding of the same on the beam, to the end that the drawing-in or entering of the warp through the harness and reed 10 of the loom may be facilitated, and also to facilitate the twisting in of a new warp when the same runs out.

It is the usual practice in the winding of a beam for use in a loom to preliminarily wind the warp 15 from the creels on a series of section beams, each containing a proportional number of the ends which are to be wound on the loom beam. Subsequently the warp from the section beams is passed through the slasher and then rewound on the 20 loom beam.

Heretofore it has been customary when a lease was to be formed in the warp to use an even number of section beams as no method has heretofore been available which would permit the formation 25 of a single end lease in the warp if an odd number of section beams were used. This requirement sometimes necessitated the use of an extra section beam when an odd number would have had sufficient capacity to take care of all the warp 30 ends required to be wound on the beam for use in the loom.

The principal object of the present invention is to provide a method of and apparatus for forming a lease in the warp which permits the formation 35 of such a lease notwithstanding the warp may be preliminarily wound on an odd number of section beams, although the method and apparatus are equally adaptable for use in connection with an even number of section beams.

With the aforementioned object in view, the present invention contemplates the provision of a novel form of leasing comb or reed, and a novel manner of manipulating the warp with respect thereto, whereby a lease may be formed in the 45 warp whether the same be fed from an odd or even number of section beams.

The nature and characteristic features of the present invention will be more readily understood from the following description taken in connection with the accompanying drawings forming part hereof, in which:

Figure 1 is a front elevation, partly broken away, of a leasing comb constituting the principal novel portion of a preferred form of apparatus for carrying out the present invention;

Fig. 2 is a transverse vertical section thereof taken on the line 2—2 of Fig. 1;

Fig. 3 is an elevational view of a fragmentary portion of a leasing reed involving a modified form of construction, also adaptable for carrying 5 out the invention;

Fig. 4 is a transverse vertical section thereof taken on the line 4—4 of Fig. 3;

Fig. 5 is a longitudinal section illustrating, to a certain extent diagrammatically, the first step in 10 the formation of a lease in accordance with the present invention;

Fig. 6 is a similar view illustrating the second step in said method;

Fig. 7 is a similar view illustrating the third 15 step in said method;

Fig. 8 is a similar view illustrating the fourth and final step in the formation of the lease;

Fig. 9 is an elevational view of a fragmentary portion of a leasing reed embodying another 20 modified form of construction, particularly adaptable for use in the same location and in a manner somewhat similar to that of the ordinary form of hook reed at present in common use; and

Fig. 10 is a transverse vertical section thereof 25 taken on the line 10—10 of Fig. 9.

Referring now more particularly to Figs. 1 and 2 of the drawings, there is there shown a form of construction of a leasing comb 14 embodying the principal features of the present invention and adaptable for use in connection with the method thereof. Said device comprises a suitable frame 15 having side struts 16. Disposed between the side struts 16 are the dents 17, suitably spaced and rigidly secured at their 30 lower ends in the frame 15 in the usual manner of construction of soldered reeds.

Each of the dents 17 there shown comprises a thin flat strip of metal provided near its upper end with offsets 18 and 19, preferably two or more 40 in number in each dent, as the provision of a plurality of said offsets in each dent will serve to prevent distortion of the individual dents. Furthermore, the offsets of each dent are staggered with relation to the offsets of adjacent 45 dents so that said offsets will in each instance bear against a portion of the adjacent dent which lies in the main plane thereof, and which is resilient to a sufficient extent to permit the warp to pass into the dent spaces during the initial 50 entering of the warp.

In the form of leasing comb shown in Figs. 1 and 2 of the drawings, each alternate dent is provided in its upper portion with a pair of struck-up hook members 20 and 21, the opening 55

of said hook members being disposed toward the central portion of the comb. The other alternate dents are provided in their lower portions with similar struck-up hook members 22 and 23, 5 also open toward the center of the comb. In each instance the hook members of each dent are disposed one on each side thereof extending into the dent spaces so as to selectively engage the warp when same is manipulated in the manner to be hereinafter set forth.

In order to prevent the warp from fouling with the spacing offsets when the said warp is manipulated to form the lease, there may be provided a cap 34 removably mounted on the 15 comb and having plate members 35 and 36 extending down from the top respectively on the front and rear faces of the comb. The lower edge 37 of the plate 35 is so positioned, when the cap is in place, that the warp ends, when elevated as hereinafter described will be prevented from fouling on the spacing offsets 18 and 19 of the dents. The cap 34 is made removable with respect to the frame so that the same may be detached when it is desired to enter the warp 25 in the comb.

In Figs. 3 and 4 of the drawings there is illustrated a form of hook reed also embodying the structure of the invention, and adaptable for carrying out the method thereof. In this form 30 of construction there are provided main dents 17^a which extend from top to bottom and are secured in the usual manner of securing the dents in soldered reeds.

There are also provided both at the top and 35 the bottom a series of auxiliary dents 24 and 25 respectively which extend part way toward the center of the reed. Near the top of the structure there are inserted metallic blocks 26, preferably of solder or the like, one of these 40 blocks being inserted between each alternate dent and the auxiliary dents on each side thereof. Each of these blocks is located a short distance above the inner end of the auxiliary dent, thereby to provide a hook like structure 20^a and 21^a 45 on each side of each alternate dent respectively near the top of the reed.

A similar arrangement is provided near the lower end of this reed, the metallic blocks 27, 50 however, being inserted between the other alternate dents and the auxiliary dents on each side thereof, the said blocks also being located a short distance below the free ends of the auxiliary dents, thereby to provide hook like structures 22^a and 23^a for the selective engagement 55 of the warp ends during the latter stages of the leasing operation.

In Figs. 5 to 8 inclusive, there is shown the manner of manipulation of the warp with respect to either the leasing comb or the reed hereinbefore described. The warp, after leaving the slasher, passes over a guide rod or roller G¹, extends through the leasing comb 14 by means of which the lease is formed, and then passes over another guide rod or roller G². The usual 60 series of separator rods s¹, s² and s³ are also provided, there being one of these for the warp coming from each section beam on which the warp is primarily wound from the creel, the warp from each section beam passing over its 65 respective separator rod.

For the purpose of illustration, there are shown 70 three separator rods as would be employed when the warp is primarily wound on three section beams. However, in the practice of the present 75 invention any number of section beams may be

employed, whether the same be odd or even, so long as there is provided one separator rod for the warp from each section beam. The separator rods are supported in suitable racks or stands (not shown) between the guide rod G¹ 5 and the leasing comb 14. These racks or stands are arranged so that each separator rod occupies two different positions in the formation of the lease, the rods being moved successively from one position to the other as will be hereinafter 10 more fully set forth.

The leasing comb 14 is so mounted that the same may be shifted sidewise with respect to the warp as is customary in the use of the common form of hook reed used for leasing and, if 15 desired, mechanism (not shown) of the same type as is used for shifting the common form of hook reed may be used for this purpose or the same may be shifted by hand.

However, in the preferred manner of carrying out the method of the present invention, the leasing comb 14 is also shifted to upper and lower positions respectively at different stages in the formation of the lease.

The first step in the formation of the lease 25 is shown in Fig. 5 of the drawings. In this instance, the comb or reed is in its lower position and the separator rods s¹, s² and s³ are in their rearmost positions, that is, adjacent to the guide rod or roller G¹. It will be noted that in this 30 position the warp from all the section beams extends through the dent spaces of the leasing comb 14 between the hooks in the upper portion thereof and the hooks in the lower portion thereof.

The comb is now shifted sidewise with respect to the warp, whereupon the separator rod s¹ is moved from its rearward position as shown in Fig. 5 to the forward position as shown in Fig. 6. The warp which passes over the separator rod 40 s¹ will thus be raised. However, the ends in this section of the warp which are disposed in alternate dent spaces will be caught by the hooks 20 in the upper portion of the comb, whereas the ends in the other alternate dent spaces will be 45 raised free of the hooks, thus causing a separation of the alternate ends of this section of the warp.

The comb is then again shifted sidewise with respect to the warp but in the opposite direction 50 after which the separator rod s² is moved forward from its rearward position to raise the section of the warp controlled thereby. In this manner the section of the warp controlled by the separator rod s² will also be separated, it being noted, however, that in this instance the ends which are disposed in the dent spaces in which they were previously permitted to pass freely above the hooks will now be caught in said hooks 21, whereas in the dent spaces where the ends of the 60 previous section were caught by the hooks 20, the ends will now be permitted to pass freely upward. The action is again repeated with respect to the warp ends controlled by the separator rod s³ also causing a separation of the alternate ends 65 in that section.

Assuming that there are but three sections of the entire warp, the same will now be separated in each alternate dent space with two ends engaged by the hooks and one end elevated above 70 the hooks, while in the other alternate dent spaces one end will be engaged by the hook and the other two ends raised above the hook. The warp being thus separated into two sheets as shown at the forward end of Fig. 6, the leasing cord or rod 75

L^1 is inserted in the shed like space thus provided and the first part of the lease is formed.

The leasing comb 14 is now raised to the position shown in Fig. 7 of the drawings, causing all of the warp to be free from engagement by the hooks of the comb. A reverse actuation of the separator rods is now effected step by step. The leasing comb, however, being in the proper position so that when the separator rod s^3 is returned from its forward to its rearward position, the warp ends controlled thereby will be lowered.

However, the ends disposed in alternate dent spaces will be engaged by the hooks 22 in the lower portion of the comb, and in the other alternate dent spaces they will be permitted to be depressed below said hooks. Likewise with the warp ends controlled by the separator rods s^2 and s^4 , the leasing comb in each instance being shifted sidewise to selectively engage or permit the warp ends to pass in alternate dent spaces as may be required to form the lease.

When all of the separator rods are returned to their initial positions, the warp will again be separated by the leasing comb into two sheets as shown at the forward end of Fig. 8 and in the shed like space thus provided between the two sheets of warp the leasing cord or rod L^2 is inserted to complete the formation of the lease. The leasing comb may now be lowered to its initial position and the warp thereafter fed through the same free of engagement by the hooks thereof.

It will be noted that by the employment of the method and apparatus hereinbefore described, a lease may be readily formed without regard as to whether the number of sections of the warp be odd or even.

It should, however, be understood that it is not essential that the hooks be provided in both the top and bottom portions of the comb or reed, or that the comb or reed be so positioned with respect to the slasher that the lease is formed after the warp has passed through the slasher.

By way of example, there is shown in Figs. 9 and 10 of the drawings, a form of reed embodying certain features of the present invention and adaptable for use in the same location as hook reeds of the common form are now used for forming the lease before the warp passes through the slasher. This reed is formed in a manner somewhat similar to that of the ordinary hook reeds. In this form of construction there are provided main dents 17^b which extend from top to bottom where they are secured in the usual manner of securing dents in soldered reeds. There are also provided in this instance, at the top only, a series of auxiliary dents 24^b which extend part way toward the center of the reed. In connection with these auxiliary dents there are also provided inserted metallic blocks 26^b preferably of solder or the like, one of these blocks being inserted between each alternate dent and the auxiliary dents on each side thereof. Each of these blocks is located a short distance above the inner end of the auxiliary dent, thereby to provide hook like structures 20^b and 21^b respectively on each side of the alternate dent spaces near the top of the reed. Near the bottom of the structure there are also provided inserted metallic blocks 28 preferably made of solder or the like, one of these blocks being provided between each alternate pair of main dents, these blocks being similar to and used for the same purpose as such blocks are used in the common form of hook reed. As these blocks in the lower portion of the frame form no

essential part of the present invention, the same need not be further referred to.

A single end lease may be formed by use of the structure of the top portion of the reed shown in Figs. 9 and 10 of the drawings in a manner similar to that by which the lease is formed in the use of either of the structures shown in Figs. 1 and 2 or 3 and 4 of the drawings, the only difference being that, after the first lease rod or cord is inserted as in Fig. 6 of the drawings, the separator rods are all returned to their initial positions before beginning the formation of the second part of the lease. In the formation of the second part of the single end lease the reed is shifted sidewise with respect to the warp in directions opposite to those used for the first part. In the formation of a single end lease the reed is also used in the same horizontal position during the formation of the lease, and is not raised and lowered as is done where the leasing hooks are provided in both the upper and lower portions of the frame.

It should also be understood that various other changes and modifications may be made in the structure of the reed or comb without departing from the spirit of the present invention.

I claim:

1. The method of forming a lease in a warp made up of a plurality of sections which consists of disposing in each dent space of a comb or reed one thread from each section of the warp, transposing the sections of the warp from one position to another in succession, hooking the threads in alternate dent spaces as each section is transposed thereby to separate the warp of each section into two parts, inserting a lease member in the separation, then unhooking the threads, thereafter again transposing said warp sections in succession, hooking the threads of each section in alternate dent spaces as the same are thus transposed, thereby to again separate said warp into two parts, and then inserting another lease member in the second separation.

2. The method of forming a lease in a warp made up of a plurality of sections which consists of disposing in each dent space of a comb or reed one thread from each section of the warp, transposing the sections of the warp from one position to another in succession, hooking the threads in alternate dent spaces as each section is transposed thereby to separate the warp of each section into two parts, inserting a lease member in the separation, then unhooking the threads, thereafter returning said warp sections in succession and in reverse order to their original positions, hooking the threads of each section in alternate dent spaces as the same are being returned to their initial positions thereby to again separate said warp into two parts, and then inserting another lease member in the second separation.

3. The method of forming a lease in a warp made up of a plurality of sections which consists of disposing in each dent space of a comb or reed one thread from each section of the warp, raising the sections of the warp from one position to another in succession, hooking the threads in alternate dent spaces as each section is raised thereby to separate the warp of each section into two parts, inserting a lease member in the separation, then unhooking the threads, thereafter lowering said warp sections in succession and in reverse order, hooking the threads of each section in alternate dent spaces as the same are lowered thereby to again separate said warp into

two parts, and then inserting another lease member in the second separation.

4. The method of forming a lease in a warp made up of a plurality of sections which consists of passing each section of the warp over a separator rod and disposing in each dent space of a comb or reed one thread from each section of the warp, manipulating said separator rods to transpose said sections of the warp from one position 10 to another in succession, hooking the threads in alternate dent spaces as each section is transposed thereby to separate the warp of each section into two parts, inserting a lease member in the separation, then unhooking the threads, 15 thereafter manipulating the separator rods to return said warp sections in succession and in reverse order to their original positions, hooking the threads of each section in alternate dent spaces as the same are being returned to their 20 initial positions thereby to again separate said warp into two parts, and then inserting another lease member in the second separation.

5. The method of forming a lease in a warp made up of a plurality of sections which consists of passing each section of the warp over a separator rod and disposing in each dent space of a comb or reed one thread from each section of the warp, manipulating said separator rods to raise said sections of the warp in succession, 25 hooking the threads in alternate dent spaces as each section is raised thereby to separate the warp of each section into two parts, inserting a lease member in the separation, then unhooking the threads, thereafter manipulating the separator rods to lower said warp sections in succession and in reverse order, hooking the threads of each section in alternate dent spaces as the same are being lowered thereby to again separate said warp into two parts, and then inserting another lease member in the second separation.

6. The method of forming a lease in a warp which consists of transposing said warp in sections from one position to another in succession, hooking alternate threads in each section of said 45 warp as the same are transposed thereby to separate said warp into two parts, inserting a lease member in the separation, then unhooking the threads, thereafter again transposing said warp sections in succession, hooking alternate threads 50 in each section of said warp as the same are thus transposed thereby to again separate said warp into two parts, and then inserting another lease member in the second separation.

7. The method of forming a lease in a warp 55 which consists of transposing said warp in sections from one position to another in succession, hooking alternate threads in each section of said warp as the same are transposed thereby to separate said warp into two parts, inserting a lease member in the separation, then unhooking the threads, thereafter returning said warp sections in succession and in reverse order to their original positions, hooking alternate threads in each section of said warp as the same are returned 60 65 thereby to again separate said warp into two parts, and then inserting another lease member in the second separation.

8. The method of forming a lease in a warp 70 which consists of raising sections of the warp in succession, hooking alternate threads in each section of said warp as the same are raised thereby to separate said warp into two parts, inserting a lease member in the separation, then unhooking the threads, thereafter lowering said warp sections in succession and in reverse order, hook-

ing alternate threads in each section of said warp as the same are lowered thereby to again separate said warp into two parts, and then inserting another lease member in the second separation.

9. The method of forming a lease in a warp 5 which consists of passing said warp in sections over separator rods, manipulating said separator rods to transpose said warp sections in succession from one position to another, hooking alternate threads in each section of said warp as the same are transposed thereby to separate said warp into two parts, inserting a lease member in the separation, then unhooking the threads, thereafter manipulating the separator rods to return said warp sections in succession and in reverse order 10 to their original positions, hooking alternate threads in each section of said warp as the same are returned thereby to again separate said warp into two parts, and then inserting another lease member in the second separation. 15 20

10. The method of forming a lease in a warp which consists of passing said warp in sections over separator rods, manipulating said separator rods to raise said warp sections in succession, hooking alternate threads in each section of said 25 warp as the same are raised thereby to separate said warp into two parts, inserting a lease member in the separation, then unhooking the threads, thereafter manipulating the separator rods to lower said warp sections in succession and in 30 reverse order, hooking alternate threads in each section of said warp as the same are lowered thereby to again separate said warp into two parts, and then inserting another lease member in the second separation. 35

11. A warp leasing device comprising a frame, a series of dents mounted therein spaced from each other to provide dent spaces therebetween in which the warp is disposed, each alternate dent having at its upper portion a pair of warp engaging hooks extending respectively into the dent spaces on each side thereof, the other alternate dents each having at its lower portion a pair of warp engaging hooks extending respectively into the dent spaces on each side thereof. 40 45

12. A warp leasing device comprising a frame, a series of dents mounted therein spaced from each other to provide dent spaces therebetween in which the warp is disposed, each alternate dent having at its upper portion a pair of warp 50 engaging hooks extending respectively into the dent spaces on each side thereof, the other alternate dents each having at its lower portion a pair of warp engaging hooks extending respectively into the dent spaces on each side thereof, the hooks of each set of dents being open in directions toward the hooks of the other set. 55

13. A warp leasing device comprising a frame, a series of dents mounted therein spaced from each other to provide dent spaces therebetween in which the warp is disposed, each alternate dent having at one portion thereof a pair of warp engaging hooks respectively extending into the dent spaces on each side thereof, and the other alternate dents each being without obstructions to the 60 free passage of the warp at the portions thereof adjacent said hooks, and each having, spaced from the aforesaid warp engaging hooks, another pair of warp engaging hooks extending respectively into the dent spaces on each side thereof. 65

14. A warp leasing device comprising a frame, a series of dents mounted therein spaced from each other to provide dent spaces therebetween in which the warp is disposed, each alternate dent having at one portion thereof a pair of warp en- 70 75

gaging hooks respectively extending into the dent spaces on each side thereof, and the other alternate dents each being without obstructions to the free passage of the warp at the portions thereof adjacent said hooks, and each having, spaced from the aforesaid warp engaging hooks, another pair of warp engaging hooks extending respectively into the dent spaces on each side thereof, the hooks carried by one set of alternate dents opening in a direction opposite to that of the hooks carried by the other set of alternate dents.

15. A warp leasing device comprising a frame, a series of dents mounted therein spaced from each other to provide dent spaces therebetween in which the warp is disposed, each alternate dent having at its upper portion a pair of warp engaging hooks extending respectively into the dent spaces on each side thereof and the other alternate dents each being without obstructions to the free passage of the warp at the portions thereof adjacent said hooks, and obstructions arranged intermediate said hooks and the lower ends of the dents, said obstructions being disposed in alternate dent spaces and extending between adjoining pairs of dents.

16. A warp leasing device comprising a frame, a series of dents mounted therein spaced from each other to provide dent spaces therebetween in which the warp is disposed, each alternate dent having at its upper portion a pair of warp engaging hooks extending respectively into the dent spaces on each side thereof and the other alternate dents each being without obstructions to the free passage of the warp at the portions thereof adjacent said hooks, and metallic blocks

arranged intermediate said hooks and the lower ends of the dents, said blocks being disposed in alternate dent spaces.

17. A warp leasing device comprising a frame, a series of dents mounted therein spaced from each other to provide dent spaces therebetween in which the warp is disposed, each alternate dent having at its upper portion a pair of warp engaging hooks extending respectively into the dent spaces on each side thereof and the other alternate dents each being without obstructions to the free passage of the warp at the portions thereof adjacent said hooks, and metallic blocks arranged intermediate said hooks and the lower ends of the dents, said blocks being disposed in alternate dent spaces for completely blocking the passage of warp thereby.

18. In the formation of a lease in a body of warp threads the steps which comprise transposing sections of said warp in succession from said body to a position spaced from the initial location of said body, hooking alternate threads in each section of said warp during the transposition of said section thereby to separate said warp into two parts, and inserting a lease member in the separation.

19. In the formation of a lease in a body of warp threads the steps which comprise raising sections of said warp in succession from said body to a position spaced from the initial location of said body, hooking alternate threads in each section of said warp during the raising of the same thereby to separate said warp into two parts, and inserting a lease member in the separation.

FRANK H. KAUFMANN. 35
